UNITED STATES PATENT OFFICE.

GEORGE M. PARKER, OF ST. LOUIS, MISSOURI.

FURNACE WALL.

Application filed June 5, 1925. Serial No. 35,150.

This invention relates to furnace walls of the kind that are provided with ducts or passageways through which air is circulated so as to prevent the wall from becoming 5 overheated and also in order to utilize the heat of the wall to heat air which is admitted to the furnace chamber.

One object of my invention is to provide a ventilated furnace wall that has a renewable 10 front portion composed of elements which are combined with a permanent portion of the wall in such a manner that they can be easily detached from said permanent portion when they become defective 15 and replaced by perfect elements.

Another object is to provide a ventilated furnace wall that has a renewable front portion of which is supported at numerous points throughout its area from the permanent 20 back portion of the wall, thereby eliminating the possibility of the front portion of the wall, which is subjected to the greatest heat, from breaking down or crumbling, as so often occurs in walls of the type in which 25 the lower part of the front portion of the wall supports and carries the entire weight of the portion of the wall above it.

And still another object is to provide a ventilated furnace wall having the desirable 30 characteristics above mentioned, that is inexpensive to build and easy to erect and repair. Other objects and desirable features of my invention will be hereinafter pointed out.

35 Figure 1 of the drawings is a front elevational view of a ventilated furnace wall constructed in accordance with my invention.

Figure 2 is a horizontal sectional view, taken on the line 2—2 of Figure 1.

40 Figure 3 is a vertical sectional view, taken on the line 3—3 of Figure 1.

Figures 4, 5 and 6 are vertical sectional views, illustrating various ways of causing air to circulate through a wall of the construction shown in Figures 1 to 3.

45 Figure 7 is a front elevational view, illustrating a modification of my invention.

Figure 8 is a vertical sectional view, taken on the line 8—8 of Figure 7; and

50 Figure 9 is a vertical sectional view, illustrating still another form of my invention.

My invention is applicable to various

kinds of ventilated furnace walls, such, for example, as the side walls and bridge wall of a boiler setting, and the elements which form 55 the front face of the wall can be combined in various ways with the permanent back portion of the wall. In Figures 1 to 6 of the drawings I have illustrated my invention embodied in a furnace wall that comprises a permanent back portion A built of brick or any other suitable material, and a renewable front portion made up of relatively large tile B and B' combined with 60 said permanent back portion A in such a manner that the renewable front portion of the wall is supported at numerous points 65 throughout its area and is capable of being rebuilt or repaired without disturbing said back portion A. Preferably, the tiles B 70 are provided on their rear sides with horizontally-disposed devices or shanks 1 that are interlocked with the permanent back portion of the wall in such a way that they can be easily detached from same, and the 75 tile B' are arranged in horizontal courses between the tile B, as shown in Figure 1, and are interlocked with each other and with said tile B by co-operating ribs and grooves 80 on the edges of said tile, as shown clearly 85 in Figures 2 and 3, wherein the reference character 2 designates a horizontally-disposed rib on the bottom edge of each tile that projects into a groove formed in the top edge of the adjacent tile on which it is 90 superimposed, and the reference character 3 designates a vertically-disposed rib on one 95 side edge of each tile that projects into a groove in the edge of the adjacent tile. The shanks or rearwardly-projecting devices 1 90 on the tile B are constructed so that they not only serve to detachably connect the renewable front portion of the wall to the permanent back portion A, but they also sustain and carry the load of said front portion or renewable portion and hold it spaced away from the back portion A so as to form air ducts or passageways α through which air is circulated to prevent said renewable front portion from becoming overheated and 100 in order to obtain superheated air which can be introduced into the chamber of the furnace above or below the fuel grate, as indicated in Figures 2 to 6. So far as my in-

vention is concerned, it is immaterial how the air is circulated through the wall, and the particular means employed to introduce the heated air into the furnace chamber is 5 also immaterial, but one convenient way of constructing the wall is to provide it with one horizontal course of tile C equipped with horizontally-disposed slots 4 disposed to form substantially a continuous horizontal 10 slot through which the heated air enters the furnace chamber from the air ducts or circulating passageways α behind the renewable front portion of the wall.

As shown in Figures 2 and 3, the back portion 15 A of the wall is provided with a pocket 5 for each of the shanks or rearwardly-projecting devices 1 on the tile B, and removable retaining elements 6 are arranged in said pockets above said shanks, as shown in Figure 3, so as to prevent said shanks from moving upwardly out of interlocking engagement with the permanent portion A of the wall. Various means can be used for interlocking the tile B with the permanent portion 20 of the wall so as to prevent said tile B from pulling away from the permanent portion of the wall, but in the form of my invention illustrated in Figures 1 to 6 each of the shanks 1 is provided at its outer end with 25 a flared or substantially dove-tail-shaped head 1^a that fits in a correspondingly shaped recess in the permanent portion of the wall located below the pocket 5 previously referred to, said recess being preferably 30 formed by special blocks D built into the permanent portion A of the wall and provided with tapered surfaces that co-operate with each other, as shown in Figure 2, so as to form vertically-disposed slots of substantially 35 the same cross-sectional shape as the shanks 1 and the flared heads 1^a on same. If desired, each of the blocks D can be provided on its front side with a forwardly-projecting rib 7 that serves as an abutment 40 or bearing surface for two of the abutting tile B that form part of the renewable front face of the wall, the rib 7 being so proportioned as to co-operate with the shanks 1 and the tile B to form vertical ducts or passageways 45 through which the air can circulate.

In erecting the wall the permanent back portion of the wall is first built of brick or any other suitable material and the special blocks D are incorporated in same so as to 55 form a plurality of undercut recesses or openings in said permanent portion arranged below pockets 5 which are large enough to receive the flared heads 1^a on the shanks 1 of the tile B. In building the renewable front 60 portion of the wall the tile B and B' are laid up in horizontal courses and the shanks 1 of the tile B are interlocked with the blocks D in the permanent portion A of the wall by introducing said shanks horizontally into 65 the pockets 5 and then moving them down-

wardly so as to insert the flared or dove-tail-shaped portions 1^a of the shanks 1 in the undercut recesses formed by the blocks D in permanent portion A of the wall. As each horizontal course of tile B is laid up and interlocked with the permanent back portion of the wall, retaining devices 6 are slipped into the pockets 5 above the shanks 1, so as to eliminate the possibility of any of the blocks B accidentally moving out of interlocking engagement with the back portion A of the wall. If one of the tile B becomes defective it is only necessary to knock out the tile B' above same, then remove the retaining device 6 from the pocket 5 in the portion A of the wall, and thereafter move the defective tile B upwardly so as to disengage the shank of same from the part in the back portion of the wall with which it is interlocked and also break the portions at the side edges of said defective tile which interlock with the tile between which it is positioned. A perfect tile B can then be substituted for the defective tile and interlocked with the back portion A of the wall, and thereafter a perfect tile B' can be arranged in operative position above the new tile B that was inserted. Due to the fact that the tile B and B' are interlocked with each other by co-operating ribs and grooves on the edges of said tile, it is necessary to remove said ribs from replacement tile that are inserted in the front portion of the wall to repair the same.

The air inlet tile C, previously referred to, can be arranged at any point in the wall where it is desired to admit heated air to the furnace chamber, and the permanent portion A of the wall can either be provided with flues 8, as shown in Figures 5 and 6, from which ducts lead to the air circulating passageway between the permanent and renewable portions of the wall, or the permanent portion of the wall can be provided with numerous air inlets 9, as shown in Figure 4, through which air enters directly to the air circulating passageway between the permanent and renewable portions of the wall.

In Figures 7 and 8 of the drawings I have illustrated another form of my invention, wherein the renewable front portion of the wall is made up of a plurality of tile B¹⁰, each of which is provided on its rear side with a shank or rearwardly-projecting device 100 that is equipped with an angularly-disposed flange or head piece 100^a, and the permanent back portion A' of the wall is provided with horizontally-disposed slots 101 constructed so as to permit the shanks of the tile B¹⁰ to be inserted in same and then slid horizontally longitudinally of the wall into operative position. As shown in Figure 7, each of the horizontal slots 101 in the permanent back portion of the wall is pro-

vided at one point with a notch or extension 102 of sufficient size to permit the head piece 100^a on the shank of any of the tile B¹⁰ to be inserted in same and then moved laterally out of alignment with said notch, thereby securely locking said tile to the permanent back portion A' of the wall. After the tile B¹⁰ have been laid up and interlocked with the back portion of the wall, as above described, one vertical row of key tile B¹¹ are incorporated in the renewable front portion of the wall so as to complete the face of the wall and prevent lateral movement of the tile B¹⁰ in a direction to disengage the flanged head pieces on the shanks of same from the horizontal slots provided for same in the back portion of the wall. In such a wall the elements B¹⁰ that constitute the face of the wall which is subjected to the greatest heat are supported from the permanent back portion A' of the wall in the same way as in the form of my invention illustrated in Figures 1 to 6; they are held spaced away from the back portion of the wall so as to permit air to be circulated over the rear side of the renewable portion of the wall and they can be easily disconnected from the rear portion A' of the wall when they become defective and easily replaced by perfect tile, thereby enabling the face of the wall to be repaired without disturbing the back portion of the wall.

In the form of my invention shown in Figure 9 the tile B²⁰ that form the renewable front portion of the wall are each provided with an integral shank or rearwardly-projecting device 110 that projects into a hole provided for same in the permanent back portion A² of the wall, said shank being provided in its top side with a notch 111 that is adapted to receive a retaining element 112 in the permanent portion A² of the wall that can be inserted through a hole 113 arranged above the hole which receives the shank 110. In erecting such a wall the tile B²⁰ are laid up in horizontal courses, and after one horizontal course has been completed, the tile constituting same are locked in position by means of the retaining elements 112 before the next horizontal course of tile is laid up.

Having thus described my invention, what I claim as new and desire to secure by Letters Patent is:

1. A furnace wall, comprising a permanent portion provided with pockets, a renewable portion made up of a plurality of large, flat tile arranged edgewise and spaced away from said permanent portion so as to form an air circulating passageway between said tile and permanent portion, integral, rearwardly-projecting, reduced shanks on some of said tile provided with flanged head pieces, and elements in the permanent portion of the wall constructed so as to form

undercut recesses below the pockets in said permanent portion and adapted to interlock with the head pieces on said shanks when said head pieces are introduced into said pockets and moved downwardly.

2. A furnace wall, comprising a relatively thick permanent portion, a removable portion made up of a plurality of relatively thin, rectangular solid tiles arranged edgewise and spaced from the permanent wall so as to form an air space between said walls, reduced shanks integral with certain of said tiles and extending at right angles thereto, the free ends of said shanks being interlocked with said permanent wall, and means projecting from said permanent wall and contacting with certain of said tiles for preventing the same from moving towards the permanent wall.

3. A furnace wall, comprising a relatively thick permanent portion, a removable portion made up of plurality of relatively thin, rectangular solid tiles arranged edgewise and spaced from the permanent wall so as to form an air space between said walls, reduced shanks integral with certain of said tiles and extending at right angles thereto, said shanks being detachably interlocked with the permanent wall, and means projecting from said permanent wall and contacting with certain of said tiles for preventing the same from moving towards the permanent wall.

4. A furnace wall, comprising a relatively thick permanent portion, a removable portion made up of a plurality of relatively thin, rectangular solid tiles arranged edgewise and spaced from the permanent wall so as to form an air space between said walls, reduced shanks integral with certain of said tiles and extending at right angles thereto, said shanks extending into said permanent wall, means for locking said shanks in said permanent wall, and means projecting from said permanent wall and contacting with certain of said tiles for preventing the same from moving towards the permanent wall.

5. A furnace wall, comprising a relatively thick permanent portion, a removable portion made up of a plurality of relatively thin, rectangular solid tiles arranged edgewise and spaced from the permanent wall so as to form an air space between said walls, reduced shanks integral with certain of said tiles and extending at right angles thereto, said shanks extending into said permanent wall, means for automatically locking said shanks in said permanent wall, and means projecting from said permanent wall and contacting with certain of said tiles for preventing the same from moving towards the permanent wall.

6. A furnace wall, comprising a relatively thick permanent wall, pockets formed in the inside face of the permanent wall, a re-

movable portion made up of a plurality of relatively thin, rectangular solid tiles arranged edgewise and spaced from the permanent wall so as to form an air space between said walls, reduced shanks integral with certain of said tiles and extending at right angles thereto, the free ends of said

shanks being interlocked with said permanent wall, and means projecting from said permanent wall and contacting with certain of said tiles for preventing the same from moving towards the permanent wall. 10

GEORGE M. PARKER.
